UNITED STATES PATENT OFFICE.

BEN RUBENSTEIN, OF NEW YORK, N. Y., ASSIGNOR TO RUBY LAMP MFG. CO., INC., OF NEW YORK, N. Y., A CORPORATION OF NEW YORK.

DESIGN FOR A LANTERN OR ARTICLE OF SIMILAR NATURE.

Application filed August 15, 1925. Serial No. 14,434. Term of patent 3½ years.

To all whom it may concern:

Be it known that I, BEN RUBENSTEIN, a citizen of Russia, residing at New York city, in the county of Kings and State of New York, have invented a new, original, and ornamental Design for a Lantern or Article of Similar Nature, of which the following is a specification, reference being had to the accompanying drawing, forming a part thereof.

Fig. I is an elevational view of a lantern showing my new design.

Fig. II is a plan view showing one half of the symmetrical bottom of the lantern.

I claim:

The ornamental design for a lantern or article of similar nature, as shown.

BEN RUBENSTEIN.
